US0D1096824S

(12) **United States Design Patent** (10) **Patent No.:** **US D1,096,824 S**
Chaudhri et al. (45) **Date of Patent:** **** Oct. 7, 2025**

(54) **DISPLAY SCREEN OR PORTION THEREOF WITH GRAPHICAL USER INTERFACE**

(71) Applicant: **Apple Inc.**, Cupertino, CA (US)

(72) Inventors: **Imran Chaudhri**, San Francisco, CA (US); **Jorge Fino**, San Jose, CA (US); **Stephen O. Lemay**, Palo Alto, CA (US)

(73) Assignee: **Apple Inc.**, Cupertino, CA (US)

(**) Term: **15 Years**

(21) Appl. No.: **29/868,266**

(22) Filed: **Nov. 28, 2022**

Related U.S. Application Data

(63) Continuation of application No. 29/817,122, filed on Nov. 29, 2021, now Pat. No. Des. 971,248, which is a continuation of application No. 29/751,388, filed on Sep. 21, 2020, now abandoned, which is a continuation of application No. 29/724,410, filed on Feb. 14, 2020, now Pat. No. Des. 896,835, which is a continuation of application No. 29/697,374, filed on Jul. 8, 2019, now Pat. No. Des. 875,771, which is a continuation of application No. 29/654,505, filed on Jun. 25, 2018, now Pat. No. Des. 853,429, which is a continuation of application No. 29/624,142, filed on Oct. 30, 2017, now Pat. No. Des. 821,437, which is a continuation of application No. 29/575,594, filed on Aug. 26, 2016, now Pat. No. Des. 801,367, which is a continuation of application No. 29/483,803, filed on Mar. 3, 2014, now Pat. No. Des. 765,092.

(57) **CLAIM**

The ornamental design for a display screen or portion thereof with graphical user interface as shown and described.

DESCRIPTION

The FIGURE is a front view of a display screen or portion thereof with graphical user interface showing the claimed design.

The dashed broken lines in the FIGURE show a display screen or portion thereof, and form no part of the claimed design.

The dot-dash lines in the FIGURE and the areas within the dot-dash lines show portions of the graphical user interface that form no part of the claimed design.

1 Claim, 1 Drawing Sheet
